TIE CASE

Albert Lee Branch, Richmond, Va.

Application August 31, 1937, Serial No. 161,867

3 Claims. (Cl. 206—7)

My invention consists in a new and useful improvement in tie cases and is designed to provide a device which serves as a case for men's neckties and a rack upon which the ties may be hung. I have experienced great difficulty in keeping my neckties unwrinkled when they are packed for travelling, and I have invented my improved device to provide a means for packing ties which will also serve to display the ties, on reaching a destination, and opening the case. My device protects the ties against mussing when the case is closed, and when it is opened the ties are displayed on the rack ready for use. The particularly novel and useful feature of my device is the means which I provide whereby the ties may be arranged upon the rack, and then either enclosed in the case, for travelling, or displayed after reaching a destination, without removal from the rack. I have so designed and related the parts of my device that the entire portions of the ties which are not covered by the collar and are therefore exposed when being worn, are entirely enclosed within my improved case.

While I have illustrated in the drawings and have hereinafter fully described one specific embodiment of my invention, it is to be distinctly understood that I do not consider my invention limited to said specific embodiment, but refer for its scope to the claims appended hereto.

In the drawings:

Fig. 1 is a perspective view, showing the device opened and suspended to serve as a tie rack.

Fig. 2 is a perspective view showing the device open and inverted, the ties resting within the case.

Fig. 3 is a perspective view, showing the device closed and suspended to serve as a tie case.

Fig. 4 is a side elevation of the device, in the position illustrated in Fig. 3.

Fig. 5 is a transverse horizontal section on line 5—5 of Fig. 6.

Fig. 6 is a fragmentary front elevation, showing the rack member and mounting.

As illustrated in the drawings, my improved device comprises a case C and rack R. The case C comprises the co-acting walls 1 and 2 hingedly related by the strip 3. Generally conforming to the configuration of a necktie, these walls 1 and 2 have convergent sides 4, the upper ends 5 being considerably wider than the lower ends 6. The end 6 of the wall 2 has a notch N, the side walls 7 of which are spaced at the proper distance to admit the portions of the neckties to rest upon the bottom 8 of the notch N, as will

be presently explained. The rack R is hingedly mounted on the outer face of the wall 2 and is produced by a single wire or rod suitably conformed to provide at its inner end the diametrically opposed shanks 9 and 10 rotatable in sleeves 11 suitably mounted on the wall 2, and at its outer end the loop 12, and intermediate its inner and outer ends the stop 13, the loop 12 and stop 13 being suitably spaced to admit therebetween the portions of the neckties, as will be presently explained. Mounted in the loop 12 is a strap 14 having a socket 15 co-acting with a snap-fastener 16 on the outer face of the wall 2, and a second socket 17 coacting with a snap-fastener 18 on the outer face of the wall 1, the strap 14 being adapted to pass around the edges 4 of the walls 1 and 2, as illustrated in Figs. 3 and 4. I also provide straps 19 attached to the wall 2 and having sockets 20 to co-act with the snap-fasteners 21 on the wall 1. Suitably attached to the ends 5 of the walls 1 and 2, there is a strap 22 having the keeper 23, to serve as a hanger means for my device. As illustrated in Fig. 1, this strap 22 may be slipped about a vertical supporting means, such as the mirror post P of a bureau, and the keeper 23 being properly adjusted, the strap 22 is caused to rest upon the post P and support my device. As illustrated in Fig. 3, the strap 22 may be passed over a horizontal supporting means, such as the hook H, to support my device.

From the foregoing description of the details of construction of my device, its use and operation will be obvious. The device being in the position illustrated in Fig. 1, the ties T can be hung upon the rack R which is swung outwardly from the case C to facilitate the placing of the ties thereon. As illustrated in Fig. 1, the ties T are disposed upon the rack R so that they are folded over the rack R at their middles M, and it will be noted that the loop 12 and stop 13 are properly spaced to accommodate the width of the ties at their middles M. When it is desired to encase the ties T, the rack R is swung toward the wall 2, and the strap 14 is fastened to the wall 2 by means of the socket 15 and fastener 16, thus clamping the middles M of the ties T between the wall 2 and rack R, thereby preventing accidental displacement of the ties T. The device is then inverted, as illustrated in Fig. 2, thereby causing the ends E of the ties T to pass over the end 6 of the wall 2 through the notch N. As illustrated in Fig. 2, the intermediate portions I of the ties T between the middles M and the ends E rest upon the bottom 8 of the

notch N. It is to be particularly noted that the rack R is so disposed upon the wall 2, that the distance between the rack R and the bottom 8 of the notch N is such that the portion of the tie extending from the notch N over the rack R and back to the notch N is that portion of the tie which is covered by the collar when the tie is being worn. The walls 1 and 2 are then moved toward one another, enclosing the ties T, and are fastened together by the straps 14 and 19 and their fastening means.

Having described my invention, what I claim is:

1. In a tie case, the combination of a pair of walls hingedly related; a rack comprising two shanks, a loop and a stop, the loop and stop being so disposed as to form a throat for receiving the ties; sleeves on the outer face of one of said walls, in which said shanks are pivotally mounted; and a strap mounted in said loop and having two fastener means adapted to co-act with com-

plementary fastener means on the outer face of each of said walls respectively.

2. In a tie case, the combination of a pair of walls hingedly related; a rack having a shank, a loop and a stop, the loop and stop being so disposed as to form a throat for receiving ties; a sleeve on the outer face of one of said walls, in which said shank is pivotally mounted; and a strap mounted in said loop and having fastener means adapted to co-act with complementary fastener means on the outer face of each of the said walls respectively.

3. In a tie case, the combination of a pair of co-acting cover members hingedly related; a journal bearing mounted on the outer face of one of said members; a tie-rack journaled in said bearing; and fastener means carried by said rack and adapted to be attached to each of said members to fasten the case in closed position.

ALBERT LEE BRANCH.
